LENS GRINDING AND POLISHING MACHINE

Eli Maynard Long, Geneva, N. Y., assignor to
Shuron Optical Company, Inc., Geneva, N. Y.,
a corporation of New York

Application July 26, 1937, Serial No. 155,866

12 Claims. (Cl. 51—160)

This invention relates to improvements in a lens grinding and polishing machine.

The invention pertains more particularly to a machine for grinding and polishing the surfaces 5 of toric lenses and is an improvement upon a machine of the type forming the subject-matter of my Patent No. 1,709,943, issued April 23, 1929. In the machine of that patent, the movable element (specifically the lens holder), of a grinding and polishing couple consisting of a lens holder and a lap, is actuated by the combined action of two reciprocative movements operating in directions at substantially right angles to each other, one reciprocative movement operating substantially parallel with the base axis of the lens (usually called the lengthwise stroke), and the other reciprocative movement operating substantially parallel with the cylinder axis of the lens being ground (usually called the cross stroke); and a 10 continuous variation or break-up (so-called "third movement") is introduced into the latter one only of the reciprocative movements, so that the resultant path of movement of the movable element of the grinding and polishing couple is a series of curvilinear strokes, and said movable 15 element goes through a comparatively large number of strokes before completing a cycle of operation and repeating its pattern of movement.

The efficacy of a machine of the above mentioned type is inherently limited to a certain extent for the following reasons. In the first place, each stroke must be relatively short in length, owing to the limited area of the surface of the grinding lap engaged by the lens which necessarily limits the length of the stroke of each of the two reciprocative movements. Secondly, the movable element, which is the lens holder in the machine of my patent, must move through a different path on each successive stroke, and the 20 change of path must be sufficiently great to prevent any minute inaccuracies occurring in the surface of the lap being reproduced on the lens. In other words, the lens must not be moved back and forth across the lap a large number of times 25 along substantially the same line, or else a defective or inaccurate portion of the grinding surface of the lap will produce a zone of aberration in the lens surface. If, on the other hand, the change in the path of movement of the lens between successive strokes is made too great, the 30 duration of each cycle of operation will be so reduced that the lens is moved so frequently along substantially the same path in engagement with the defective portion of the lap surface, that the 35 surface of the lens being ground will be adversely

affected thereby. As a result of these inherent limitations, machines of this type, including the machine shown in my above mentioned patent, will produce only a relatively low percentage of first quality lenses.

The main object of this invention is to produce an improved lens grinding and polishing machine wherein the relative movement of the lens and the grinding lap is produced by two reciprocative movements operating substantially normal to each other with means associated with both of said reciprocative movements and coacting therewith to break-up or vary the same, thereby producing a maximum change between successive paths of travel of the lens with respect to the grinding lap, while at the same time greatly increasing the duration of each cycle of operation, so that a lens will not be moved twice through the same path during the time ordinarily required to grind or polish a surface thereof.

Another object of this invention is to provide simple and efficient means, cooperating with the reciprocative movement operating in a direction substantially parallel with the base axis of the lens, or lengthwise stroke, for producing a fourth movement by which a variation will be introduced into said lengthwise stroke, whereby a variation in the point of reversal of the movable element of the grinding and polishing couple from the normal position of reversal of movement thereof, resulting from the combined variable reciprocative movements, is attained during the progressive grinding and polishing of a lens surface for the purpose of preventing, to a greater extent than heretofore, the formation of aberrations, 35 waves and distortions in the surface of the lens incidental to the reversal of the movable element at one and the same point.

A more specific object of the invention is to provide means whereby the extent of the lengthwise stroke of the movable element of the grinding and polishing couple, produced by that reciprocative movement operating substantially parallel with the base axis of the lens in combination with the fourth movement, may be quickly and 40 easily varied for lenses of different curvatures and types.

A further object of the invention resides in providing a novel means for producing a break-up in the stroke which may be applied to either 45 or both of the reciprocative movements.

In other words, I have endeavored to produce a slow continuous change in the length of the relative movement of a lens and the grinding and polishing surface throughout successive strokes 50

of the cycle of operation over an extended or indefinite period, and thus eliminate the formation of lines or waves in the lens surface which may cause a zone of aberration.

- 5 Other objects and advantages relative to the form and operation of the parts of the machine will more fully appear from the following description taken in connection with the accompanying drawings, in which:
- 10 Figure 1 is a top plan, partly in section, of a lens grinding and polishing machine embodying certain features of this invention, with the cover removed to show the interior parts.

Figure 2 is a vertical transverse sectional view taken on line 2—2, Figure 1, showing the cover in place and the upper portion of the means for producing and maintaining pressure upon the lens carrier arms broken away.

Figure 3 is a detail vertical longitudinal sectional view, through the lower portion of the machine, taken substantially in the plane of the line 3—3, Figure 1.

Figure 4 is an enlarged detail horizontal sectional view taken substantially in the plane of the line 4—4, Figure 3, and illustrating my novel mechanism for producing a break-up in the stroke used as a fourth movement mechanism, that is to say, applied to the drive means for producing reciprocative movement of a lens carrier element in a direction substantially parallel with the base axis of the lens.

Figure 5 is an enlarged detail sectional view taken on line 5—5, Figure 4.

Figure 6 is a detail horizontal sectional view, partly in elevation, of a modification in which my novel break-up mechanism is connected to the inner end of the main drive shaft, and is used in the place of the third movement mechanism shown connected with said shaft in Figures 1, 2 and 3, that is to say, for effecting a slow continuous change in the normal point of reversal of the movable element of the grinding and polishing couple in a direction substantially parallel with the cylinder axis of the lens.

45 Figure 7 is a detail sectional view taken on line 7—7, Figure 6.

Figure 8 is a detail sectional view taken on line 8—8, Figure 7.

Figure 9 is a detail sectional view taken in the plane of line 9—9, Figure 4.

Figure 10 is a detail sectional view taken in the plane of line 10—10, Figure 6.

55 Figures 11, 12 and 13 are diagrammatic views illustrating the lengthwise stroke or movement of the lens supporting element over the grinding face in directions substantially parallel with the base axis of the lens and illustrating the action of the drive mechanism shown in Figure 1 for producing said movement under certain predetermined adjustments.

Figure 14 is a diagrammatic view illustrating the action of the drive mechanism shown in Figure 6 for producing the cross stroke or movement of the lens supporting element over the grinding face in directions substantially parallel with the cylinder axis of the lens under certain predetermined adjustments.

Figure 15 is a diagrammatic view illustrating succeeding strokes of the lens over the grinding surface of the lap, as produced by my novel mechanism when set in the position indicated in Figures 11 and 12.

75 Figure 16 is a diagrammatic view illustrating succeeding strokes of the lens over the grinding surface of the lap as produced by the motion

break-up mechanism shown connected to the main drive shaft in Figures 1, 2 and 3.

The machine, as illustrated in the drawings, has the greater portion thereof of usual construction and operation, being similar to that shown in my above mentioned Patent No. 1,709,943. The machine is shown as being provided with a casing 1 which carries a pair of lens surface grinding and polishing couples. Each couple comprises a lap supporting element 3 fixedly secured to the front side of the casing 1, and a lens actuating or pressure arm 4 which extends from the interior of the casing 1 outwardly through a slot 5 provided in the front wall of the casing to a position over and beyond the corresponding lap supporting element 3.

A main drive shaft 6 is journaled in suitable bearings 7 and 7' provided in the casing 1 to rotate about a horizontal axis. The shaft is driven from a pulley 8 mounted thereon exteriorly of the case, said pulley being adapted to be operated by a belt from any suitable source of power, not shown.

As illustrated in Figures 1, 2 and 3 of the drawings, the inner end of shaft 6 is provided with an eccentric crank pin 10 adapted to rotate bodily about the axis of the shaft. A connecting rod or pitman 11 is rotatably mounted at one end upon the crank pin 10, while the lower end of the connecting rod is provided with a stud 12 which extends laterally therefrom in a horizontal plane substantially parallel with the axis of the pin 10.

An eccentric 13, journaled upon the stud 12, is provided with a worm gear 14 at one end thereof which is in meshing engagement with a worm 15 secured to the lower end of a vertically disposed shaft 16 which, in turn, is journaled in suitable bearings 17 and 18 provided on the connecting rod 11. The shaft 16 has secured to the upper end thereof a worm gear 20 which is in meshing engagement with a worm 21 secured to the outer end of the crank pin 10. A yoke member 23 is rotatably mounted upon the eccentric 13 and is adjustably connected to a curved portion 24 of an arm 25 by a set screw 26. The arm 25 is secured at one end, by a set screw 27, to the central portion of a rock frame 28 which is rotatably connected, by pivot pins 29, to upwardly extending posts or lugs 30 projecting from the bottom of the case 1, so that the frame 28 rocks about a horizontal axis extending substantially parallel with the axis of the drive shaft 6 and arranged in a plane at one side of said shaft. The curved portion 24 of the arm 25 is arranged concentric with and has its center of curvature approximately in the axis of the drive shaft 6, so that adjustment of the yoke 23 longitudinally of the arm 25 for varying the degree of rocking movement of the frame 28, will produce a minimum amount of tilting movement of the arm 25 and frame 28. It will be observed that the action of the eccentric 13 and its associated drive shaft 16 and gearing, is to continuously vary the effective length of the connecting rod 11 connecting the crank pin 10 and the curved arm 25, so that, for a given setting of the adjustable yoke 23, a constant angular rocking movement of the frame 28 will be produced, but the position of the rocking movement will vary slightly and continuously.

The rock frame 28 carries a pair of upright supports 32 arranged in spaced relation to each other longitudinally of the frame. Each of the supports 32 is pivotally connected to the frame 28

at opposite sides of the axis of rotation of said frame by pivotal pins 33. The supports 32 extend upwardly from the pivots 33 and each has the upper end thereof bifurcated to receive adjacent end portions of a floating frame 34 which extends in a horizontal plane above the frame 28 and is pivotally connected to the supports 32 by pivotal pins 35. It is thus seen that the floating member 34 constitutes a connecting link between the upper end of the supporting members 32, whereby the supports 32 will be simultaneously rocked in reverse directions, about the pivots 33, as the floating frame 34 is reciprocated lengthwise in a manner presently described.

15 A pair of reversely arranged substantially L-shaped arms 37 and 38 are pivotally mounted at 39 and 40, respectively, upon the floating frame 34 to swing about coaxial axes parallel with the axis of the frame 28 and drive shaft 6, the L-shaped arms 37 and 38 being movable vertically independently of each other for permitting independent operation of the hereinbefore mentioned lens carrying arms 4 which are pivoted, at 42, to the L-shaped arms 37 and 38, respectively. The pivots 42 of each lens operating arm 4 are disposed in approximately the horizontal plane of, and nearly coaxial with, the pivots 35, as shown in Figures 2 and 3, so that arms 4 may swing about parallel axes at substantially right angles to the axis of the rock frame 28 and drive shaft 6 to compensate for varying positions of their respective lens holders 43 when moving across the face of their corresponding laps 44.

The construction and operation of the mechanism thus far described is substantially the same as that shown in my Patent No. 1,709,943, and is adapted more particularly for producing reciprocative movement of the lens supporting arms 4 in directions substantially parallel with the shorter or cylinder axis of the lens. The mechanism which includes the novel features of this invention, for producing reciprocative movement of the lens supporting arms 4 in directions substantially parallel with the longitudinal or base axis of the lens, will now be explained.

The main drive shaft 6 is provided with a worm 45 positioned intermediate the bearings 7 and 7'. The worm 45 meshes with a worm gear 46 rotatably mounted upon a fixed shaft 47 secured to the casing 1 beneath the drive shaft 6 by a set screw 48, Figure 1. A yoke 50, connected with the worm gear 46 by arms 51, is rotatably mounted on shaft 47. The arms 51 cause the yoke 50 to rotate in unison with the gear 46 and form an intervening space for receiving a pair of collars 52 which are secured to the shaft 47 to hold the gear 46 and yoke 50 against axial movement with respect to shaft 47. A crank pin 54 is journaled for angular adjustment in the yoke member 50 at one side of and parallel with the stationary shaft 47. The crank pin 54 is held in different positions of angular adjustment by means of a clamping screw 55 engaged in a diametrically extending threaded aperture in the crank pin 54 and which extends outwardly from the crank pin through an elongated slot 56 provided in the adjacent portion of the yoke 50 to permit relative rotary adjustment of the screw. Mounted in the threaded aperture in the crank pin 54 is a friction block 57, positioned at the inner end of the screw 55, adapted to be brought into frictional contact with the peripheral surface of the wall of the aperture 50' receiving the crank pin 54 for releasably maintaining said crank pin against rotation relative to the yoke 50.

The crank pin 54 is provided with a reduced eccentric extension 54' which is substantially parallel with the axis of the crank pin. Rotatably mounted upon the extension 54' is an eccentric sleeve 59, upon which is rotatably mounted a drive sleeve 60 which, in turn, is pivotally connected, as at 61, to one end of a pitman 62, having its other end connected by a universal joint 63 to the floating frame 34 (see Figures 3 and 4). The outer end of the eccentric sleeve 59 has connected therewith a gear 65 which, in this instance, is of greater diameter than the sleeve 59 and coacts with an annular flange 66, provided on the crank pin 54 at the inner end of the extension 54', for maintaining the drive sleeve 60 against axial displacement. The eccentric sleeve 59 is maintained against axial displacement, relative to the extension 54', by a bracket 67 secured to the outer end portion of the extension 54', as shown in Figure 4.

20 Journaled in the bracket 67 is a stub shaft 68 arranged at one side of the extension 54' in parallel relation therewith. The shaft 68 extends outwardly at both ends beyond the sides of bracket 67 and has secured to one end thereof a pinion 69 which is in meshing engagement with the gear 65. The other end of the shaft 68 has secured thereto a gear 70 which is in meshing engagement with a pinion 71 rotatably mounted upon a reduced portion 54'' of the extension 54 and which 30 is arranged in coaxial relation with said extension 54'. To the outer end of the pinion 71 is secured an arm 72. This arm 72 is fixed to the pinion 71, extends radially therefrom and is provided with an elongated slot 72' which slidably 35 receives therein a holding pin 73 secured to the adjacent front wall of the casing 1, as shown in Figure 9. Pin 73 and slot 72' are so related to each other that arm 72 may freely move longitudinally as the gear 71 revolves about the axis of 40 shaft 47.

The lens or lenses to be ground may be fastened, in any suitable manner, to the underside of the lens holder or block 43 for reciprocative movement across and upon the upper face of the 45 lap 44, carried by the corresponding supporting element 3 for grinding and polishing purposes. It will be understood that the outer end portions of lens actuating arms 4 may each be moved toward and from the lap supporting elements 3 50 independently of each other, by any suitable means, to permit the removal and replacement of the lens holder 43, while the lens carried by the holder may be yieldingly held in pressure engagement with the lap 44 by any suitable means, 55 as by an upright pressure rod 76 and a spring 77, portions of which are shown in Figure 2.

60 It will now be observed that when the main drive shaft 6 is being rotated, a lens, carried by one of the arms 4 in pressure engagement with the corresponding lap 44, will be moved across the grinding surface of the lap with a curvilinear movement compounded of two reciprocative movements operating at right angles to each other and two break-up movements, each of the 65 latter movements being associated with a respective one of the reciprocative movements.

To explain more explicitly, the rotation of crank pin 10 about the axis of shaft 6 will produce a rocking movement of the frame 28 about 70 the pivots 29. This rocking movement of frame 28 will produce a corresponding reciprocative movement of the upper portion of the supports 32 and the arms 4 carried thereby in a direction substantially parallel with the cylinder axis of 75

the lens mounted on said arms, inasmuch as the axes of pivots 29 extend in a plane substantially normal to the cylinder axis of the lens. At the same time, the rotary movement of eccentric 13, produced by the gear members 21 and 20, shaft 16 and gear members 15 and 14, will cause a relatively slow independent movement of the yoke 23 and arm 25 in the direction of the length of the connecting rod 11, and this independent movement is transmitted to the arm 4 and lens actuated thereby through the frame 28, supports 32, frame 34 and arms 37 and 38, thereby causing a continually varying effective length of the connection between the driving shaft 6 and arm 25 which, in turn, causes a continually changing scope and field of action of the lens holder and lens carried thereby across the grinding surface of the lap, as indicated in Figure 16, in the same manner as shown and described in my Patent No. 1,709,943.

In my novel drive mechanism, the lens actuating arms 4 and the lens connected therewith are reciprocated longitudinally of the lap 44 by the rocking of frame 34 and supports 32 about the axes of the pivots 33 and 35, produced by the crank pin 54 as the same is rotated about the axis of shaft 47, through the medium of the drive sleeve 60 and crank arm 62. During this rotary movement of the crank pin 54, the length of the lengthwise stroke of the floating frame 34 will be constantly changing due to a continually varying effective length of the crank arm connection between the axis of shaft 47 and the connecting rod 62. This continuously varying effective crank arm length is produced by the rotation of eccentric sleeve 59 upon the crank pin extension 54', during the revolution of the crank pin 54, caused by the rotary movement transmitted to the gear member 65 by the pinion 69 which, in turn, is rotated by shaft 68 and gear 70, as the latter gear is rotated about the relatively fixed gear 71 by the bracket 67.

The effect of the combined action of crank pin 54 and eccentric sleeve 59 upon arms 4 will possibly be more clearly understood by referring to the diagrammatic views, Figures 11, 12 and 13, wherein the point 47 represents the axis of the shaft 47; the points 54 represent the axis of the crank pin 54 mounted in the yoke 50; the points 54' represent the axis of the crank pin extension 54'; and the points 59 represent the axis of the eccentric sleeve 59; the two sets of points 54, 54' and 59 in each figure being represented in different positions 180° apart. The full and broken lines 62 represent the connecting rod 62 in its extreme forward and back positions. Line 34 represents the frame 34 and lines 32 represent the supports 32. The circle X represents the path of movement of the crank pin 54 about the axis of the shaft 47, while the circle Y represents the path of movement of the axis of the crank pin extension 54' about the shaft 47. Circle X' indicates the possible path of movement of the axis of the extension 54' during adjustment of said crank pin within the yoke 50, while the circle Y' represents the path of movement of the axis of the eccentric sleeve 59 about the axis of the crank pin extension 54' during the rotation of the sleeve upon the extension.

It will now be evident that when the crank pin 54 is adjusted relative to the yoke 50 to obtain the maximum degree of travel of the crank pin extension 54' about the axis of the shaft 47, as shown in Figures 11 and 12, the lens carrier pin 4' connected with the lens carrier arm 4 will be

moved a maximum distance over the grinding surface of the lap 44 as the crank pin 54 revolves about the shaft 47.

It will also be obvious that inasmuch as the eccentric sleeve 59 is being constantly rotated at a relatively slow rate of speed, the longitudinal center of the sleeve 59 will be slowly rotated about the axis of the extension 54', thereby constantly varying the effective length of the crank connection between the axis of shaft 47 and the connecting rod 62, and causing each arm 4 to move through gradually varying distances within the limits shown by the full and broken lines 4 in Figure 11. In other words, the arm 4 will move between the positions obtained by the maximum degree of throw produced by the combined action of the crank pin and eccentric sleeve, as shown in Figure 11, and the minimum degree of throw as shown in Figure 12.

The setting of the crank pin 54 to obtain the maximum degree of movement of the lens carrier arm 4 is utilized with a lens having a substantially flat surface or one in which the curve of the surface being ground has a relatively long radius. When the surface of the lens being ground has a relatively short radius, the crank pin 54 is adjusted in the yoke 50 to bring the axis of the extension 54' thereof into relatively close relation with the axis of the shaft 47. When the crank pin 54 is thus adjusted to obtain the minimum degree of action produced by the crank pin, as indicated diagrammatically in Figure 13, the carrier arm 4 will obviously have a much less degree of movement than with the previously described adjustment of the crank pin.

It will be observed, however, that owing to the driving connections between the crank pin extension 54' and the eccentric sleeve 59 and the relatively slow speed of rotation of the eccentric sleeve thus produced, the position of the point of connection between the arm 62 and sleeve 60 is continuously but slowly changing with respect to the axis of extension 54' and that at every revolution of the eccentric 59 upon the extension 54', the ball and socket connection 63 is being moved toward and from the extension 54' a distance corresponding to twice the throw of the eccentric sleeve. It, therefore, follows that the arm 4 and lens holder actuated by frame 34 will not only be caused to travel through continuously changing paths or fields of action, but the ends of succeeding strokes thereof are constantly changing position, diagrammatically shown in Figure 13, which reduces to a minimum the liability of scoring or otherwise injuring the lens as the lens is moved longitudinally of the base curve of the lap 44 by any errors or imperfections in the grinding surface of the lap.

The above described action of the crank pin extension 54' and eccentric sleeve 59, upon the frame 34 and arms 4, is equally true when the crank pin 54 is adjusted to obtain the minimum degree of travel of the lens across the lap 44, as shown in Figure 13, wherein the minimum and maximum amount of travel of an arm 4, for such adjustment, is indicated at *a* and *b* respectively.

In Figures 6, 7, 8 and 10, I have illustrated the use of my novel break-up mechanism for the purpose of producing the break-up movement of the cross stroke, that is to say, applied to the means for reciprocating the floating frame 34 in directions parallel with the cylinder axis of the lens and lap. In this structure, the drive shaft 6 has the crank pin 10 thereof rotatably supporting the eccentric sleeve 59 and gear 65, while the bracket 71

67 is secured to the outer end of the crank pin 10. This bracket 67 rotatably carries the shaft 68, which in turn has the pinion 69 secured to one end and the gear 70 secured to the other end thereof. The pinion 69 is in meshing engagement with the gear 65 while the gear 70 is in meshing engagement with the pinion 71 which is journaled on an extension 10' provided on the outer end of the crank pin 10 in coaxial relation therewith.

The pinion 71 is maintained against rotation during the rotation of the extension 10' about the axis of the shaft 6 by a pair of links 80 which are pivotally connected, as at 81, Figure 10, to each other. One of the links is pivotally connected, as at 82, to the rear wall of the casing 1, while the other link is fixedly secured to the pinion 71.

Rotatably mounted upon the eccentric sleeve 59 is a connecting rod 84 which extends downwardly from the eccentric sleeve and carries at its lower end a stud 85. This stud 85 is arranged in the connecting rod 84 to extend therefrom in substantially parallel relation with the axis of the drive shaft 6 and has rotatably mounted on the outer end thereof a yoke 86, similar to the yoke 23 shown in Figure 2. This yoke 86 is provided with an aperture extending therethrough substantially normal to the stud 85 for receiving the curved end portion 24 of the arm 25. The yoke 86 is adjustably secured to the arm 25 by a set screw 87.

In the construction shown in Figure 6, the effective length of the crank arm connection between the axes of shaft 6 and connecting rod 84 is constantly changing, as illustrated diagrammatically in Figure 14, due to the continuous but relatively slow rotation of the eccentric sleeve 59 upon the crank pin 10, as the crank pin 10 revolves about the axis of the shaft 6. This continuous rotation of eccentric sleeve 59 upon crank pin 10 is caused by the rotary movement transmitted to the gear 65 by pinion 69 as explained hereinbefore for the structure shown in Figure 4. This gradual increase or decrease in the effective length of the crank arm connection between the axis of shaft 6 and rod 84 produces a corresponding variation in the length of the stroke thereof and the angular extent of the rocking movement of the frame 28, which movement is transmitted through the supports 32, frame 34 and arms 37 and 38 to the lens actuating arms 4 and the lens actuated thereby.

In other words, when the stud 85 has been moved to its extreme up position by the combined action of the eccentric sleeve 59 and the crank 10, through the medium of the connecting rod 84, in which position the high point of the eccentric sleeve 59 is directly over the axis of the stud 85, then the point of connection between the arm 25 and yoke 86 will assume a position at A, Figure 14, at the upper limit of the movement of the stud 85. When the crank pin 10 has been moved 180° to its lowermost position and the eccentric sleeve has been rotated so that the longitudinal center thereof lies directly below the axis of the stud 85, then the point of connection between the arm 25 and yoke 86 will assume a position at A' at the extreme lower position of its movement. These extreme positions of the point of connection between the yoke 86 and the arm 25 will produce corresponding extreme positions of the actuating arm 4 and the lens connected therewith relative to the grinding surface of the lap 44, as indicated respectively by full lines and broken lines in Figure 14. Owing to the

driving connections between the crank pin 10 and the eccentric sleeve 59 and the relatively slow speed of rotation of said sleeve produced by said connection, the effective length of throw of crank pin 10 is continually but slowly changing. At 5 every changing of the length of this throw, a corresponding change in the length of the cross stroke of arms 4 is produced even as the length of the lengthwise stroke is continually changing when my novel motion break-up mechanism is 10 mounted on crank pin 54 as explained hereinbefore and as illustrated in Figure 15.

It will now be clear that when my novel break-up mechanism is applied to the means for reciprocating the lens longitudinally of the grinding surface of the lap, as shown in Figure 1, the center of each reciprocative stroke will be substantially coincident with the minor axis of the lap as illustrated in Figure 15, wherein line N—N represents the minor axis of the grinding lap 20 and lines M represent succeeding strokes of a pin 4' lengthwise of the lap. Also, it will be understood that when my novel break-up mechanism is applied to the means for producing the cross stroke, or for moving the lens transversely of the grinding surface of the lap, as shown in Figure 6, it will likewise produce strokes which are of varying lengths, and wherein the centers of the strokes, as indicated by line N—N, Figure 15, extend in a straight line, are substantially 30 coincident with the major axis of the lap.

It therefore follows that the combination of the two circular movements produced by my novel break-up mechanism with the two reciprocative movements will produce a continuous change in 35 the position of the ends of the succeeding strokes of the lens across the grinding surface of the lap due to the continually changing lengths of both the lengthwise and cross strokes.

If, however, the motion break-up mechanism 40 applied to the cross stroke is substantially the same, as that shown in my Patent No. 1,109,943, and illustrated in Figures 1 and 2 of this application, the general direction of movement of the lens across the face of the lap is through a more 45 or less serpentine path, as illustrated in Figure 16 of the drawings wherein the line O—O represents the major axis of the grinding lap, lines M' represent succeeding cross strokes of a pin 4' upon the lap, and line P—P represents the 50 center line of each stroke. These differences in the character of the variations introduced into the lengthwise and cross strokes when my novel break-up mechanism is applied to the drive pin 54; and the break-up mechanism shown applied 55 to the crank pin 10 in Figures 1 and 2, are due to the fact that in the break-up mechanism shown in Figure 4 the rotation of the eccentric sleeve 59 causes a change in the effective throw of said 60 sleeve and has the effect of continually increasing or decreasing the eccentricity of the crank pin 54 with a resultant increase or decrease in the length of the stroke produced by the combined action of the eccentric sleeve 59 and crank pin extension 54', illustrated by Figure 15. In the break-up mechanism connected with crank pin 10, Figures 1 and 2, the rotation of the eccentric 65 13 produced by the gear members 21 and 22, shaft 16 and gear members 15 and 14, has the effect of continuously increasing or decreasing the length of the connecting rod 11, while maintaining a substantially uniform length of stroke because the throw of eccentric 10 remains constant. A corresponding change is thus produced 70 75

in the position but not in the length of the cross stroke of arms 4, as illustrated by Figure 16.

It will be seen from the foregoing that the resultant effect produced by my novel break-up mechanism, when used in connection with the lengthwise stroke in combination with the break-up mechanism shown in Figures 1 and 2, connected with the cross stroke, upon each of the arms 4 and the lens holder actuated thereby will 10 be to reverse their motion at constantly changing points during succeeding strokes while the general field of operation thereof is maintained substantially constant. This is due to the lengths of the longitudinal strokes being constantly varied, as shown in Figure 15, while the length of the cross strokes are maintained substantially equal, but the general field of operation thereof is constantly changing as indicated in Figure 16. In other words, whether my novel break-up mechanism is used in connection with the cross stroke, as shown in Figure 6, or the break-up mechanism, shown in Figures 1 and 2, is associated with the cross stroke, the combination of either of these movements with the break-up mechanism, shown 20 connected with the lengthwise stroke, when combined with the two reciprocative movements, will produce a continuous change in the position of reversal of movement of the lens across the grinding surface of the lap during each succeeding stroke without materially decreasing the length of the stroke produced by the combined action of the two reciprocative movements. At the same time the cycle of operation or the period between the operation of the lens a second time 30 through a given path is greatly lengthened by the combined action of the two circular movements. In fact, in the machine of the present invention, the period from the beginning of operation until the lens begins to travel the second time through the original path of movement has been so increased that such a condition will 40 not occur during the grinding or polishing of a given lens.

In the machine shown in Figures 1 to 5 of the drawings, each cycle of operation actually continues without repeating any stroke for several hours of operation, while the operation of the machine of one grinding or polishing operation seldom exceeds twenty minutes. On the other hand, in the machine of my Patent No. 1,709,943, in which only the variation produced by the co-action of gears 14, 15, 20 and 21 and eccentric sleeve 13 in connection with the cross reciprocating movement is employed, the cycle of operation repeats about once every minute or in about every 450 revolutions of the drive shaft 6. Furthermore my novel break-up mechanism is applicable for introducing a variation into either the cross stroke or the lengthwise stroke or both, but this is not true of the break-up mechanism of my said patent which is applicable only in connection with the cross stroke as illustrated therein. It is thus evident that the efficiency of the machine of the present invention is materially increased over that of said patent and a resultant increase in the percentage of first quality lenses, as that term is understood in the optical industry, is obtained with the machine of this application.

70 Although the construction and operation of the novel features of the mechanism above described are particularly simple, practical and efficient, I do not wish to be limited thereto as it is evident that various changes may be made 75 in the detail construction without departing from

the spirit of the invention as set forth in the appended claims.

I claim:

1. In a lens grinding and polishing machine having a lens grinding element and a lens holding element mounted in cooperative relation with each other, in combination, operating mechanism for producing relative movement of said elements to effect grinding of the lens carried by the holding element comprising two operating members, two drive means, one for each operating member, means operatively connecting said drive means with the operating members for producing reciprocative movement of each operating member in directions substantially normal 15 to the reciprocative movement of the other operating member, each of said connecting means including a break-up mechanism adapted to cause variations in the reciprocative movement produced by said connecting means to effect operation of the operating member through continuously changing paths, and means for simultaneously operating said drive means.

2. A lens grinding and polishing machine as in claim 1 wherein at least one of said break-up 25 mechanisms is of such a character that the action produced thereby is to constantly vary the length of each succeeding reciprocative stroke of the operating member operated thereby.

3. A lens grinding and polishing machine as in 30 claim 1 wherein at least one of said break-up mechanisms is of such a character that the action produced thereby is to constantly vary the position of the center of each succeeding stroke of the member actuated thereby.

4. In a lens grinding and polishing machine having a lens grinding element and a lens holding element mounted in cooperative relation with each other, in combination, operating mechanism for producing relative movement of said 40 elements to effect grinding of the lens carried by the holding element comprising two operating members, two drive means, one for each operating member, means operatively connecting said drive means with the operating members for 45 producing reciprocative movement of each operating member in directions substantially normal to the reciprocative movement of the other operating member through continuously changing paths, and means for simultaneously operating 50 said drive means, one of said connecting means including a mechanism for constantly varying the length of each succeeding reciprocative stroke of the member operated thereby while maintaining the center of said strokes substantially constant with respect to a plane extending 55 therethrough normal to said strokes and the other connecting means including mechanism for constantly varying the position of the center of each succeeding stroke of the member actuated 60 thereby lengthwise of the strokes while maintaining said strokes of the member at a substantially uniform length.

5. A lens grinding and polishing machine as in claim 4 having means adjustable at will connected with said operating mechanism for varying 65 the amount of movement of each operating member.

6. In a lens grinding and polishing machine having a lens grinding element, a lens holding 70 element, and operating means comprising relatively movable members for one of said elements, in combination, a rotary drive shaft, mechanism connected with certain of the movable members 75 of the operating means and actuated by said

shaft for imparting a reciprocating movement to the element actuated by said operating means in a predetermined direction with respect to the other element, separate mechanism connected with the other of said movable members and actuated by the driveshaft for imparting a reciprocating movement to said element actuated by the operating means in a direction substantially normal to the first mentioned direction of movement thereof with respect to the other element, each of said mechanisms including a break-up means actuated thereby for automatically varying the normal path of movement of the element actuated by the operating means in each of said reciprocating directions during each revolution of the drive shaft.

7. A device as in claim 6 wherein one of said drive mechanisms includes means adjustable at will for varying the amount of movement of said members of the operating means and of said element carried thereby.

8. In a lens grinding and polishing machine having a lens grinding element, a lens holding element and a movable driving means for one of said elements, in combination, means for operating the driving means including a drive member mounted to rotate about a fixed axis, a crank member connected with the drive member in eccentric relation therewith to revolve about said fixed axis, an eccentric member rotatably mounted on the crank member, means rotatably connected to the eccentric member for actuating the driving means to and fro for producing reciprocation of said element actuated thereby in a predetermined direction with respect to the other element, means actuated by the revolving motion of the crank member for rotating the eccentric member relative to said crank member for varying said path of reciprocating movement of said element including a train of gears mounted on the crank member to revolve therewith about said fixed axis, each gear of said train being adapted to rotate relative to said crank member, and means connected with one of the gears of said train for holding the same stationary with respect to its axis of rotation.

9. A device as in claim 8 having means for adjusting the crank member toward and from said fixed axis to alter the path of travel thereof about said fixed axis.

10. In a machine for grinding lenses or the like having a grinding element and a work supporting element, means connected with one of said elements for producing movement thereof relative to the other element comprising an eccentric mem-

ber having an axis of rotation, operating means rotatably supporting the eccentric member adapted to revolve said member about a second axis arranged in spaced substantially parallel relation with said axis of rotation, means for rotating the eccentric member comprising a drive element having an axis of rotation, means rotatably supporting said drive element in coaxial relation with the eccentric member and adapted to revolve said drive element about said second axis in unison with the eccentric member, holding means connected with the drive element having movement therewith during the revolution thereof about said second axis and adapted to maintain said element against rotation about the axis of rotation, and separate rotatable means movable in unison with the operating means about said second axis and actuated by the drive element for producing rotation of said eccentric member about said axis of rotation thereof.

11. A machine of the class described in claim 10, wherein the operating means includes relatively movable members adjustable with respect to each other for producing relative movement of the axis of rotation of the eccentric member and said second axis toward and from each other, and means for releasably securing said members in the adjusted position.

12. In a lens grinding machine having a grinding element and a work holding element mounted in cooperative relation with each other and wherein an actuating arm connected with at least one of said elements is operated by means comprising a pair of reciprocative members and drive elements operatively connected with said reciprocative members and mounted to revolve about fixed axes for producing relative movement of the work carried by the holding element and said grinding element in grinding engagement with each other by the combined action of two reciprocative movements operating in directions substantially normal to each other, in combination, separate operating means including a pair of eccentric sleeves and drive members therefor actuated by the revolving motions of the drive elements, said sleeves and drive members being so constructed and arranged that two reciprocative break-up motions are produced by two circular motions and said break-up motions combine with said reciprocative movements respectively for continuously changing the point of reversal of movement of said element connected with the actuating arm resulting from said reciprocative movements.
